UNITED STATES PATENT OFFICE.

CHARLES GIOVANNONI, OF ENTERPRISE, OREGON.

WIRE-CLAMP FOR INSULATORS.

1,118,545.

Specification of Letters Patent. Patented Nov. 24, 1914

Application filed January 12, 1914. Serial No. 311,715.

To all whom it may concern:

Be it known that I, CHARLES GIOVANNONI, a citizen of the United States, residing at Enterprise, county of Wallowa, and State 5 of Oregon, have invented certain new and useful Improvements in Wire-Clamps for Insulators, of which the following is a specification.

This invention relates to wire clamps for 10 insulators.

My invention relates to that class of devices used in connection with electrical insulators for affording a quickly applied and secure means for connecting an electric conductor, whether telegraph, telephone or 15 power wire, to the insulator without having to resort to the old style of tie wire twisted around the conductor.

My object is to provide an improved wire 20 clamp of few parts, simple, inexpensive, strong and durable construction wherein wire clamp plates, a yoke, and an abutment block are of improved construction and combined together in a novel manner, permitting 25 rapid and easy attachment to the insulator and co-operation with the groove in said insulator and with the conductor wire to hold the conductor securely to the insulator and permit it to be easily applied 30 or removed therefrom.

One embodiment of the invention is set forth fully hereinafter and the novel features are recited in the appended claims.

In the accompanying drawings: Figure 1 35 is a plan view showing parts of the device in section and illustrating it as applied to an insulator which is in section; Fig. 2, a detail vertical section taken through the center of the clamp plates, showing the coil spring; Fig. 3, a similar view taken through 40 the end parts of the clamp plates, showing the springy lips; Fig. 4, a view looking toward the inside of one of the clamp plates; Fig. 5, a detail perspective of the yoke; and 45 Fig. 6, a similar view of the clamp plate and abutment member.

The conductor clamp consists of two elongated plates 1 and 2 having outwardly flared flanges 3 at their ends. One of the 50 plates has a longitudinal bottom flange 4 to support the other and inner plate. One or both of the plates may be provided with struck-up springy lips 5 or with springy lips 55 connected thereto, these being preferably located at the end parts of the clamp. Interposed between the clamp plates, and pref-

erably secured to one of them, as for instance, the outer plate, and at a point intermediate the length thereof is a coil spring 6. The coil spring 6 is under compression 60 when the clamp plates are clamped against the conductor wire which is shown at 7, but when said clamp plates are loosened, the spring 6 spreads them apart, permitting the conductor to be easily inserted between the 65 clamp plates or removed therefrom. The supplemental springs 5 assist the coil spring 6 in the aforesaid operation and, due to the location of these spring devices 5 and 6, the clamp plates are substantially uniformly 70 spaced when the said plates are released from tension. I do not limit myself, however, to the number, location, or form of the springs 5 and 6, except where specified in the claims. I may dispense with the lips 75 5 or, if they are used, provide lips which are of a small amount or practically no resiliency and merely use them as spacing devices subject, however, to yield when the clamp plates are tightened against the conductor. 80

An abutment member 8 is suitably fastened by a rivet 8^a to one of the wire clamp plates, the said abutment member being substantially semi-circular in form and provided with an internal ridge or rib 9 which is adapted to fit in the groove of the insulator. This abutment member has outer grooves 10 in line with the rib 9. 85

A U-shaped yoke 11 whose intermediate 90 arched part is adapted to lie in the groove of the insulator, has legs which are received in the grooved parts 10 and whose extremities are screw-threaded at 12 and pass through sets of elongated slots 13 and 14 in 95 the clamp plates and carry clamping wing nuts 15. The yoke and abutment member completely embrace the insulator and engage the circumferential groove thereof, when the device is clamped in position, and 100 it is therefore impossible for the wire clamp to slip on the insulator. The wing nut 15 serves the double purpose of clamping the plates 1 and 2 on the conductor and of clamping the yoke and the abutment member 105 around the insulator.

With the present invention, the old form of tie wire is entirely eliminated and telephone, telegraph or other electric conductors may be quickly and easily attached to their 110 insulators, or replaced or repaired.

Having thus described my invention, what

I claim as new and desire to secure by Letters Patent, is:

1. In a wire clamp, the combination of clamp plates adapted to open and close and to engage a conductor, spring means adapted to open said clamp plates, spacing devices interposed between the clamp plates and adapted to facilitate the opening action of the spring means thereon, and means for attaching the clamp plates to an insulator and for closing them against the spring action aforesaid.
2. In a wire clamp, the combination of clamp plates adapted to hold a conductor therebetween, yieldable spacing lips on the inner face of one of said clamp plates, and means for connecting the clamp plates to an insulator.
3. In a wire clamp, the combination with clamp plates, of an arc-shaped abutment member attached thereto and having free, oppositely extending, parts adapted to engage the groove of an insulator on one side of the latter, and a yoke adapted to engage

said groove on the opposite side of the insulator, said yoke being connected to the clamp plates and adapted to interlock with the free parts of the abutment member beyond the clamp plates and at the side of the insulator. 25

4. In a wire clamp, the combination with clamp plates, of an arc-shaped abutment member carried by one of said plates and having free oppositely extending parts which have an internal rib adapted to enter the groove of an insulator and are provided 30 with external grooves, and a securing yoke engaged with the clamp plates, said yoke being adapted to engage the groove of the insulator on the opposite side thereof from the abutment member and having its legs 35 lying in the grooves in the free parts of the abutment member. 40

In testimony whereof, I hereunto affix my signature in presence of two witnesses.

CHARLES GIOVANNONI.
